CLAIM

The ornamental design for a display device screen with
graphical user interface, as shown and described.

DESCRIPTION

The FIGURE is a front view of a display device screen with
graphical user interface showing the claimed design.

The innermost perimeter broken line notched rounded rectangle
shows the display screen and forms no part of the
claimed design. The two outer perimeter broken line
rounded rectangles and the broken line semicircle at the
bottom of the design show environmental subject matter and
form no part of the claimed design. The remaining broken
lines illustrate portions of the graphical user interface that
form no part of the claimed design.
